UNITED STATES PATENT OFFICE.

FRANK W. KENNEDY, OF TRENTON, NEW JERSEY, ASSIGNOR TO DE LAVAL STEAM TURBINE COMPANY, OF NEW YORK, N. Y., A CORPORATION OF NEW JERSEY.

ROTOR CONSTRUCTION.

1,075,577.

Specification of Letters Patent.

Patented Oct. 14, 1913.

Application filed February 17, 1913. Serial No. 743,917.

To all whom it may concern:

Be it known that I, FRANK W. KENNEDY, a citizen of the United States of America, and resident of Trenton, in the county of Mercer and State of New Jersey, have invented certain new and useful Improvements in Rotor Construction, of which the following is a specification.

My invention relates to improvements in rotor construction, particularly applicable to the rotors of steam turbines, but also applicable to centrifugal pumps; and my invention comprises improved means for securing a plurality of bucket wheels or other 15 rotor-sections to a shaft which such rotor-sections drive, or by which they are driven.

My invention consists in the features hereinafter described and particularly pointed out in the appended claims.

20 The object of my invention is to improve the construction of rotors, and particularly to provide improved means for securing rotor sections to their shafts.

I will now proceed to describe my invention with reference to the accompanying drawings, and will then point out the novel features in claims.

Figure 1 shows a fragmentary longitudinal section of a steam turbine comprising a 25 plurality of bucket wheels secured to a shaft in accordance with my invention; Fig. 2 shows a transverse section on the line $\alpha-\alpha$ of Fig. 1; Fig. 3 shows a fragmentary longitudinal section of a centrifugal pump, the 35 impellers of which are secured to the pump shaft in accordance with my invention.

Referring first to Figs. 1 and 2, 1 designates the shaft of the turbine, and 2 the turbine casing. 3 designates the usual dia- 40 phragms dividing the interior of the turbine casing into a plurality of wheel-chambers, and provided with nozzle-apertures 4. 5 designates a ring, formed separately from shaft 1, but secured rigidly to said shaft, 45 as for example, by being shrunk on to said shaft. In practice, before this ring 5 is allowed to grip the shaft it is positioned accurately on said shaft both longitudinally and angularly. 6—6 designate bucket 50 wheels, mounted somewhat loosely on shaft 1; they may have a drive fit on the shaft, but are not keyed to the shaft, except as herein-after described. 7—7 designate rings which slide over the ends of the shaft. They may 55 be secured against angular rotation with re-

spect to the shaft by keys 8; but such keys are not necessary in most cases. 9—9 designate spacing rings between the several bucket wheels. The ring 5, the bucket wheels 6, the end rings 7 and the spacing rings 9 60 are bored for the reception of through bolts 10, of which four are used in the construction shown in Figs. 1 and 2. These through bolts are provided at their ends with suitable screw nuts 11, and serve, in connection 65 with said nuts, to clamp the bucket wheels and spacing rings together, and further serve, in connection with the fixed ring 5, and also in connection with the rings 7, when the latter are keyed to the shaft, as shown, to 70 prevent rotation of the bucket wheels with reference to the shaft.

In constructing the parts of the turbine, after the ring 5 has been shrunk upon the shaft, said ring is carefully turned externally and is ground at the sides to true surfaces. The bucket wheels 6, and spacing rings 9 are similarly ground at the sides so that all can fit closely together. The ring 5 is carefully located angularly, with respect to the key slots for the keys 8 (if such keys are to be employed) so that when the parts are assembled the holes in said ring 5 for the through bolts 10 will register with the holes in the rings 7 for such through 85 bolts, when the keys 8 are in place. The bucket wheels and spacing rings, when placed on the shaft, are similarly aligned so that their holes for the passage of the through bolts will register with the holes 90 for the through bolts of ring 5. The rings 7 are then applied and the through bolts passed through the registering holes and the nuts 11 applied and screwed up, the pressure exerted by said screw nuts against the 95 rings, and so against the bucket wheels and the spacing rings 9, pressing these members together very tightly; so much so that the frictional engagement of these members is ordinarily sufficient to preclude any relative rotation of any of the members on shaft 1, without putting any particular transverse stress on the through bolts 10; but, as above stated, keys 8 may be provided for the rings 7; whereby these through bolts are held at 105 the ends as well as in the center against lateral motion. This method of securing the several parts of the rotor together obviates occasion for the provision of long key ways in the shaft, and corresponding keys; and 110

by this construction the several parts of the rotor may be secured together and secured to the shaft against rotation very quickly and at very little expense.

A similar construction is applicable to centrifugal pumps as illustrated in Fig. 3 wherein 12 designates the pump shaft, 13 the pump casing, 14 the impellers mounted upon said shaft, 15 a ring mounted upon said shaft 12, and corresponding to the ring 5 of Fig. 1, and 16 designates spacing rings between the several impellers. 17—17 designate end bushings corresponding to the end rings 7 of Fig. 1. In Fig. 3 I have not shown the bushings 17 as keyed to the shaft 1. 10 designates a through bolt, as in Fig. 1, and 11—11 end nuts.

What I claim is:

1. A rotor construction comprising in combination a shaft, a ring secured thereto, rotor members mounted on said shaft, said rotor members and fixed ring provided with one or more registering bolt-apertures, and one or more through bolts passing through said bolt-apertures and provided with means for pressing the several rotor members together against said fixed ring, whereby the frictional engagement of said members with each other and with the fixed ring, supplemented if occasion arises by the keying action of such through bolt or bolts, secures the several rotor members against rotation with respect to said shaft, the said rotor members comprising also end rings through which the said bolt or bolts pass, and keys securing said end rings against rotation with respect to said shaft.

2. A rotor construction comprising in combination a shaft, a ring secured thereto, rotor members mounted on said shaft, said rotor members and fixed ring provided with one or more registering bolt-apertures, and one or more through bolts passing through said bolt-apertures and provided with means for pressing the several rotor members together against said fixed ring, whereby the frictional engagement of said members with each other and with the fixed ring, supplemented if occasion arises by the keying action of such through bolt or bolts, secures the several rotor members against rotation with respect to said shaft.

3. A rotor construction comprising in combination a shaft, a ring secured thereto, rotor members mounted on said shaft, said rotor members and fixed ring provided with one or more registering bolt-apertures, and one or more through bolts passing through said bolt-apertures and provided with means for pressing the several rotor members together against said fixed ring, whereby the frictional engagement of said members with each other and with the fixed ring, supplemented if occasion arises by the keying action of such through bolt or bolts, secures the several rotor members against rotation with respect to said shaft, the said rotor members comprising also end rings through which the said bolt or bolts pass, and keys securing said end rings against rotation with respect to said shaft.

4. A rotor construction comprising in combination a shaft, a ring secured thereto, rotor members mounted on said shaft, said rotor members and fixed ring provided with one or more registering bolt-apertures, and one or more through bolts passing through said bolt-apertures and provided with means for pressing the several rotor members together against said fixed ring, whereby the frictional engagement of said members with each other and with the fixed ring, supplemented if occasion arises by the keying action of such through bolt or bolts, secures the several rotor members against rotation with respect to said shaft, the said rotor members comprising also end rings through which the said bolt or bolts pass, and keys securing said end rings against rotation with respect to said shaft.

5. A rotor construction comprising in combination a shaft, a ring secured thereto, rotor members mounted on said shaft, said rotor members and fixed ring provided with one or more registering bolt-apertures, and one or more through bolts passing through said bolt-apertures and provided with means for pressing the several rotor members together against said fixed ring, whereby the frictional engagement of said members with each other and with the fixed ring, supplemented if occasion arises by the keying action of such through bolt or bolts, secures the several rotor members against rotation with respect to said shaft, the said rotor members comprising also end rings through which the said bolt or bolts pass, and keys securing said end rings against rotation with respect to said shaft.

In testimony whereof I have signed this specification in the presence of two subscribing witnesses.

FRANK W. KENNEDY.
